 werk, Siemensstadt near Berlin, Germany

Application February 25, 1937, Serial No. 127,617
 In Germany March 6, 1936

24 Claims. (Cl. 179—16)

In automatic telephone systems the cost of the devices individual to each subscriber's line plays an important part in the total cost of the system. Accordingly it is desirable to re-use devices already on hand, particularly subscribers' lines when erecting new exchanges or extending systems already in existence. In the case of exchanges adapted for loop impulsing difficulties are involved with lines having a high resistance or leakages. It has therefore been proposed to operate with alternating current in the case of such subscribers' lines while the usual operation with exchange battery is employed for lines which are in good condition.

Such a non-uniform mode of operation which naturally can also be employed for new systems if very long subscribers' lines are involved, is made possible in a simple manner according to the invention and without the provision of special devices in the exchange for each type of differently equipped subscriber's line.

This is achieved in that the subscribers' stations disposed in lines having a high resistance or leakages are arranged for induced current impulsing and devices serving to receive the induced impulses are so arranged in the exchange devices which are likewise accessible to subscribers' lines employing loop impulsing that an impulse receiving relay, which is under the influence of the impulse circuit in the case of calls from subscribers' stations employing loop impulsing, is brought under the influence of the devices for receiving the induced impulses in the case of calls from subscribers' stations employing induced current impulsing, which receiving devices receive the induced impulses transmitted from the calling station and transmit these to the impulsing receiving relay for normal impulses in correspondence with the interruptions in the loop at the calling station.

The present invention also relates to a circuit for an impulse receiving device for systems in which numerical impulse receivers are set by the transmission of induced impulses.

In the case of the transmission of induced impulses an impulse to be transmitted is determined by a disconnecting and a connecting impulse or by a connecting and disconnecting impulse on the primary side of the repeater. Thus for each impulse transmitted two successive impulses in opposite directions operate on the secondary side of the repeater.

Such impulses can seldom be transmitted with the desired uniformity as regards their length, strength and time displacement on account of

the conditions of operation which have to be considered in the case of a system such as that under consideration.

The invention relates to an impulse receiving device for receiving and repeating induced impulses which is insensitive as regards the above shortcomings and effects efficient reception of the induced impulses and their transmission and conversion to normal current impulses without necessitating special construction.

This is achieved in that by the individual successive induced impulses two impulse receiving relays for receiving and repeating the impulses are alternately brought under the influence of the impulse circuit.

An embodiment of the invention is illustrated in the drawing, but the invention is not to be considered limited to this embodiment. T_n represents a subscriber's station, the devices of which are so arranged that on initiating a call a loop is established whereupon impulses are transmitted as normal D. C. impulses when the loop is interrupted. T_n' represents a subscriber's station at which on initiating a call an induced impulse is transmitted whereupon on subsequently operating the dial, induced impulses are transmitted for setting succeeding numerical impulse receivers. AS represents a call finder which has access both to subscribers' stations employing loop impulsing and also to subscribers' stations employing inductive impulsing. Similarly, over the final selector LW variously equipped subscribers' stations can be reached.

When the subscriber at station T_n takes up his receiver relay R is energized over the leads La and Lb . Relay R operates its contacts and at contact $1r$ characterizes the calling subscriber in the contact bank of the testing wiper asc of the call finder. Contact $2r$ sets up a start circuit over which relay An is energized in the following circuit: earth, battery, resistance W_1 , contacts $2r$, $21t$, relay An , earth. Relay An energizes relay $R2$ in the following circuit earth, contacts $3an$, $11p$, relay $R2$, battery, earth. Relay $R2$ prepares the testing circuit of the call finder at contact $5r2$. At contact $4r2$ the rotary magnet Das of the call finder is operated in the following circuit: earth, interrupter Un , contact $4r2$, rotary magnet Das , contact $8p$, battery, earth. When the call finder finds the calling line the following circuit is established for relays P and T : earth, contact $5r2$, windings II and I of relay P , wiper asc , contact $1r$, relay T , battery, earth. Relays P and T energize. Contact $9p$ establishes a circuit passing over contact $48v2$ so that an-

other hunting call finder cannot be set on the line of subscriber T_n . Contact $10p$ energizes relay V . Contacts $6p$ and $7p$ switch the speaking leads L_a, L_b , through. Contact $12p$ prepares the testing circuit of the final selector which passes over the winding of relay $P2$. Contact $13p$ applies earth in preparation to contact $51a$. Relay T on energizing operates contacts $18t, 19t, 20t$ and $21t$. Contact $20t$ maintains the guarding circuit established by the testing of the call finder independent of contact $1r$. Contact $21t$ breaks the circuit for the start relay A_n so that this releases in the event of no other call occurring. Contact $3an$ is accordingly opened. After relay T has energized contact $11p$ disconnects relay $R2$ so that this restores contacts $4r2$ and $5r2$ to normal.

When the speaking leads are switched through contacts $6p$ and $7p$ relay J is brought under the influence of the loop at station T_n . Relay J accordingly energizes in the following circuit: earth, battery, relay J , contact $46g$, winding I of the repeater U_e , contact $5p$, wiper asa of the call finder, lead L_a , the loop at station T_n , lead L_b , wiper asb of the call finder, contact $7p$, winding III of the repeater U_e , contact $45g$, choke-coil $Dr1$, earth. Relay J operates its contacts and energizes relay $V1$ over contact $14j$. Contact $13j$ prepares the circuit for relay H so that this energizes when contact $15v$ closes and by opening contacts $16h$ prevents relay G from energizing over winding II . Contact $17v1$ maintains the guarding circuit passing over contact $9p$. Relay $V1$ does not release during the impulse transmission. Contact $49v1$ serves to energize relay $V2$ which switches over contact $48v2$.

Relay J which is energized over the subscriber's loop after the call finder has switched through deenergizes impulsively in response to the operation of the dial at the subscriber's station T_n . On the first impulse which is transmitted in any desired manner to a driving magnet of the final selector LW the off-normal contact kt is switched over so that when relay H is impulsively operated by contact $13j$ relay G cannot energize over contact $16h$ and its winding II .

When the final selector is stepped to a subscriber's line for example that of station T_n3 , by the impulses transmitted from the calling station. If the desired line is free relay $P2$ energizes in the following circuit: earth, contacts $12p$, windings II and I of relay P , wiper $1c$, and devices in the desired subscriber's line which are not shown. Relay $P2$ switches the speaking leads through at contacts $23p2$ and $24p2$. Contact $25p2$ establishes a guarding circuit which passes from earth over contacts $12p$ and $25p2$, winding I of relay $P2$ and wiper $1c$. Contact $25p2$ connects wiper $1d$ of the final selector to earth. However, assuming that the desired subscriber's station is adapted for loop impulsing relay M does not energize since wiper $1d$ has been set on a contact to which relay M is not connected. Ringing current is now transmitted to the called station in the known way. When the called party takes up his receiver relay Se energizes in the following circuit: earth, battery, relay Se , contact $28m$, winding II of the repeater U_e , contact $23p2$, wiper $1a$, of the final selector, the loop at the subscriber's station T_n3 , wiper $1b$ of the final selector, contact $24p2$, winding IV of the repeater U_e , contact $29m$, choke-coil $Dr2$, earth. Relay Se is operated and disconnects ringing current in any known manner. When

the speaking connection is established the subscriber at T_n3 is enabled to cause relay Se to release and reenergize by transitorily hanging up his receiver so as to enable him to signal, for example to a supervisory operator. The release of a call is under the influence of the calling party in the present embodiment.

If the final selector LW is set on a subscriber's line adapted for transmitting induced impulses relay M is operated over the common wiper $1d$ after the final selector has tested and relay $P2$ has energized and closed contact $26p2$. Relay Se is thereupon disconnected from the speaking leads through the switching over of contacts $28m$ and $29m$. Relay D is brought under the influence of the called station by contacts $21m$. Contact $30m$ prepares an energizing circuit for relay F . When the called party takes up his receiver relay D is operated by an induced impulse generated at the subscriber's station when the receiver is removed. This induced impulse is generated by a device similar to that represented at subscriber's station T_n1 . The impulse passes from the device at the subscriber's station over wiper $1a$, contacts $23p2, 27m, 35f$, relay D , contacts $31e, 24p2$, wiper $1b$, and back to the subscriber's station. Relay D energizes and switches over its contacts. At contact $32d$ it locks up. Contact $31d$ promotes the energizing of relay F in the following circuit: earth, contacts $30m, 31d$, relay F , battery, earth. Relay F operates its contacts and at contact $35f$ applies earth to the relay Se , which interrupts the transmission of ringing current in the manner already described. When the induced impulse transmitted when the party at station T_n3 takes up the receiver, has died down relay D releases. The following locking circuit is established for relay F : earth, contacts $39m, 31d$ (restored), $38e, 33f$, relay F , battery, earth. Relay E is now connected between the speaking leads over contact $34f$ and the relapsed contact $32d$, so that a second induced impulse generated when the called station replaces the receiver influences relay E . This causes relay F to deenergize on account of the opening of contact $38e$ and relay Se is deenergized by the opening of contact $35f$. When this induced impulse dies down relay F is not energized again when relay E releases since in the meantime contact $33f$ has opened. Relay D is now disposed between the speaking leads so that if the receiver at the subscriber's station is taken up again relay D and consequently also relay F energize, with the result that relay Se energizes again. In this way the called station is enabled to transmit a flicker signal.

If the call is to be released the subscriber at station T_n replaces his receiver. This results in deenergizing relay J and the slow operating relay $V1$. Relay $V1$ opens contacts $17v1$ so that relay P releases. Contact $49v1$ breaks the circuit for the slow relay $V2$, which makes a delayed release so that contact $48v2$ only restores to normal after the guarding circuit has been opened at contact $9p$. The guarding circuit passing over winding I of relay $P2$ is also broken by the release of relay P at contacts $12p$. Relay $P2$ releases and effects the restoration of the final selector LW to the normal position in any known manner. When relay P released contact $11p$ was also restored to normal so that after relay T has released the call finder AS can once more be seized.

When the subscriber at station T_n1 initiates

a call the switchhook contacts $Hu1$ and $Hu2$ are operated when the receiver is removed. The switchhook contact $Hu1$ disconnects the bell W from the speaking leads and connects up the subscriber's apparatus, repeater G , microphone M , and telephone F . On account of the switching over of contact $Hu2$ relay K is energized in the following circuit: positive pole of battery B , contact $2s$, relay K , contact nsa , which is only switched over when the dial plate is off-normal, switch-hook contact $Hu2$, and negative pole of battery B . Relay K operates its contacts, contact $4k$ closing before contact $5k$. This prevents the "make" impulse from being transmitted inductively over the leads $La1$ and $Lb1$. Contact $3k$ operates relay S over positive pole of battery B , relay S , contact $3k$, switchhook contact $Hu2$, negative pole of battery B . Contact $1s$ breaks the circuit passing over winding I of the former Tr , so that the first "break" impulse is transmitted. Relay K releases since it is short-circuited by the energizing of relay S over negative pole of relay B , contact $1s$, relay K , contact nsa , switchhook contact $Hu2$, and negative pole of battery B . Relay S remains energized over the positive pole of battery B , relay S , resistance Wi , contact $1s$, negative pole of battery B . The first induced impulse passing over the line $La1/Lb1$ energizes relay $R1$ over winding I . Relay $R1$ accordingly operates its contacts so that the following circuit is established for relay An over contacts $40r1$ and the following locking circuit for winding II of relay $R1$: earth, battery, winding II of relay $R1$, contacts $40r1$, $43t1$, relay An , earth. Relay $R1$ remains energized over its winding II after the induced impulse energizing relay $R1$ over winding I has died down. Contact $39r1$ characterizes the calling line at wiper asc of the call finder AS . On the closing of contact $3an$ earth is applied to line LL thereby starting up a free call finder. If the call finder AS which is represented in the drawing, is free, contact $11p$ will be in the normal position so that on closing contact $3an$ the following circuit is established for relay $R2$: earth, contacts $3an$, $11p$, relay $R2$, battery, earth. Relay $R2$ operates its contacts and starts the call finder shown in the drawing over contact $4r2$. The testing circuit of the call finder is prepared at contact $5r2$. When the call finder finds the calling subscriber's line the following testing circuit is set up: earth, contact $5r2$, windings II and I of relay P , contact $38r1$, relay $T1$, battery, earth. In this circuit relays P and $T1$ energize. Relay P brings the call finder to rest by opening contacts $8p$. In addition it establishes a guarding circuit by closing contact $9p$ and connecting earth directly to winding I of relay P over contact $48v2$ and contact $9p$. Relay $R2$ is caused to deenergize by contact $11p$. Contacts $6p$ and $7p$ switch the connecting line through. Through the energizing of relay $T1$ winding I of relay $R1$ is disconnected by contact $4p1$. Contact $42t1$ maintains the guarding circuit independent of contact $39r1$. Contact $43t1$ deenergizes winding II of relay $R1$. If no further impulse is received to maintain relay An energized this relay releases and opens contact $3an$. When the connecting line is switched through at contacts $6p$ and $7p$ no circuit is established for relay J over the loop at the calling station since the condenser Ko is disposed in the upper speaking lead thereat.

Since relay J does not energize when the line is switched through relay G operates over winding II in the following circuit when contact $15v$

closes as a result of relay V operating on the closing of contacts $10p$: earth, contact $15v$, off-normal contact kt , contact $16h$, winding II of relay G , battery, earth. Relay G operates its contact $44g$ thereby establishing a locking circuit for winding I of relay G . This locking circuit is independent of the state of energization of winding II of relay G . After relay G has energized relay J is operated in the following circuit: earth, contacts $13p$, $51a$, $57b$, $54c$, $46g$, relay J , battery, earth. Relay J operates its contacts and by closing contact $14j$ energizes relay VI . The guarding circuit for the call finder passing over contacts $48v2$ is maintained by the closing of contact $17v1$ before the opening of the contact $48v2$. Contact 15 $49v1$ energizes relay $V2$. Contact $48v2$ is switched over but does not promote any switching operation. Relay A was connected to the speaking leads of the connecting line by $47g$. The subscriber can now be notified that he can commence to dial by the transmission of an exchange signal in any known manner. When the subscriber operates his dial switch for the purpose of setting succeeding numerical impulse receivers contact nsa is switched over when the dial is drawn off-normal. Relay K accordingly energizes over the positive pole of battery B , contact $2s$, contact nsa , relay K , contact $1s$, and negative pole of battery B . Contact $5k$ connects winding II of the transformer Tr to lead $La1$. As the dial plate runs back contact nsa remains closed while contact nsi is intermittently operated. When the circuit is completed for the first time by contact nsi an impulse is inductively transmitted over leads $La1$ and $Lb1$ and is taken up by relay A . Relay A operates its contacts and by switching over contact $51a$ deenergizes relay J and energizes relay C in the following circuit: earth, contacts $13p$, $51a$, relay C , battery, earth. Contact $50a$ establishes a locking circuit for relay A which is maintained until the induced impulse has died down. Contact $53c$ opens the original energizing circuit for relay A . When relay A releases relay C remains operated in the following circuit: earth, contacts $13p$, $51a$, $57b$, $54c$, relay C , battery, earth. On the release of relay A relay B is connected to the speaking lead by contact $50a$ which restores to normal. When now another induced impulse is transmitted on the opening of contact nsi this is taken up by relay B whereupon relay J which released when contact $51a$ was switched over, again energizes. This circuit for relay J passes from earth over contact $13p$, $51a$, $57b$, $46g$, relay J , battery, earth. When the induced impulse has died down relay J remains energized over earth, contacts $13p$, $51a$, $57b$, $54c$, $46g$, relay J , battery, earth. Subsequent impulses are transmitted to relay J in the same way through the alternate operation of relays A and B . Relay J by releasing and reenergizing is utilized to control the final selector LW in the known manner. The final selector is stepped by this transmission of impulses in the manner already described and its operation is adapted to suit the equipment of the called station by the aid of relay M . When the dial plate at the calling station $T21$ has returned to normal, contact nsa is restored to its original position. Relay K is accordingly deenergized since it is short-circuited by the following circuit: negative pole of battery B , contact $1s$, relay K , contact nsa in its normal position, switch-hook contact $Hu2$ and negative pole of battery B . Relay K then disconnects winding II of the transformer Tr by contact $5k$ so that the subscribers who are now connected

together can converse. When the connection is to be released subscriber $Tn1$ replaces his receiver. The switchhook contacts $Hu1$ and $Hu2$ are consequently restored to normal. The following circuit is established for relay K: positive pole of battery B, contact $2s$, switchhook contact $Hu2$, contact nsa , relay K, contact $1s$, negative pole of battery B. In this circuit relay K energizes so that winding II of the transformer Tr is again connected to lead $La1$. Contact $3k$ short-circuits relay S in the following circuit, positive pole of battery B, relay S, contact $3k$, switchhook contact $Hu2$, contact $2s$, positive pole of battery B. Relay S releases. The energizing circuit provided for winding I of transformer Tr is accordingly closed at contact $1s$. This energizing of winding I of transformer Tr promotes the transmission of an induced impulse to relay A. Relay A energizing and over earth and contacts $13p$ and $5ia$ operates relay C. Relay C energizes and locks up over contact $54c$ in a circuit which becomes operative when contact $5ia$ is restored to normal when the induced impulse has died down. The energizing of relay A deenergizes relay J. At contact $14j$ relay J breaks the circuit for relay $V1$. Relay $V1$ releases and at contact $17v1$ breaks the guarding circuit in which relays P and T were held energized. Relays P and T release. The circuit for relay $V2$ is broken at contact $49v1$. When this connects earth to contact $9p$ over contact $48v2$ the former contact is already opened so that the release can proceed unhindered. On the release of relay P the circuit for relay V is opened at contact $16p$ and the circuit for relay C is opened at contact $13p$. Relays V and C release. Relay J remains deenergized. Contact $12p$ breaks the locking circuit for relay $P2$ so that this also restores to normal. The switch LW releases in known manner whereupon contact kt is restored to normal. On the opening of contact $15v$ relay G also releases.

After the transmission of the "make" impulse which serves as a release impulse by the deenergizing of relay S relay K also releases since the negative potential of the battery B is disconnected at $1s$. The induced impulse produced on the opening of contact $4k$ is not transmitted since contact $5k$ leaves its operated position before contact $4k$.

As has been described, in the present embodiment the special construction of the station $Tn1$ is characterized by the energizing of relay G. The energizing of relay G is promoted by the condenser Ko disposed in the upper speaking lead. This relay could alternatively be operated over a special wiper of the call finder as soon as the call finder becomes set on a subscriber's line employing induced impulse transmission. Relay G must then be similarly connected as is relay M in the final selector LW .

What is claimed is:

1. In a device for controlling automatic switches, a controlling relay, intermediate controlling means, a line incoming to said device, means for seizing said line and transmitting impulses thereover to operate said relay, said relay connected directly to said line and responsive to received impulses under one condition of seizure, and means effective under another condition of seizure for bringing said relay under control of said intermediate means and causing said intermediate means to respond to received impulses to in turn control said relay.

2. In a device for controlling automatic switches, a controlling relay, intermediate con-

trolling means, a line incoming to said device, means for seizing said line and transmitting impulses thereover to operate said relay, said relay connected directly to said line and responsive to received impulses under one condition of seizure, means effective under another condition of seizure for bringing said relay under control of said intermediate means and connecting said intermediate means to said line to operate said relay responsive to one received impulse and to release said relay responsive to the succeeding received impulse.

3. In an automatic switching control system, stations of one class having means for transmitting alternating current impulses over their line circuits, stations of another class having means for transmitting direct current impulses over their line circuits, switching equipment having two impulse receiving means, means for associating the line circuit of a station of either class with said switching equipment, means responsive to the association of the line circuit of a station of said one class with said switching equipment for causing said line circuit to assume control of the first said impulse receiving means, means responsive to the association of a line circuit of a station of said other class with said switching equipment for causing said last line circuit to assume control of the second said impulse receiving means.

4. In an automatic telephone system, two classes of subscriber stations and line circuits therefor, means at each station of one class for interrupting the associated line circuit to transmit impulses thereover, means at each station of the other class for transmitting impulses over the associated line circuit without interrupting said line circuit, switching equipment including two impulse receiving means, means for associating the line circuit of a station of either class with said switching equipment, means effective when the line circuit of a station of said one class is associated with said switching equipment for causing said line circuit to assume control of the first said impulse receiving means, means effective when the line circuit of a station of said other class is associated with said switching means for causing said last line circuit to assume control of the second said impulse receiving means.

5. In an automatic switching control system, stations of one class having means including impulsive contacts for transmitting over their line circuits two impulses for each operation of said contacts, stations of another class having means including impulsive contacts for transmitting over their line circuits one impulse for each operation of said contacts, switching equipment including automatic switches, switching control means, and intermediate control means, means for associating the line circuit of a station of either class with said switching equipment, means responsive to the association of the line circuit of a station of said one class with said switching equipment for placing said switching control means under control of said intermediate means and for placing said intermediate means under control of said line circuit, means effective upon the association of a line circuit of a station of said other class with said switching equipment to cause said last line circuit to assume the direct control of said switching control means, said switching control means effective to operate said automatic switches in correspondence with the impulsive contacts at a station of either class.

when the line circuit of that station is associated with said switching equipment.

6. In an automatic switching control system, two classes of stations and line circuits therefor, 5 means at stations of one class for interrupting their line circuits to transmit impulses thereover, means at stations of the other class for transmitting impulses over their line circuits without interrupting said line circuits, switching equipment, 10 means for extending the line circuit of a station of either class to said equipment, one impulse receiving means connected to the line circuit responsive to the extension thereof to said switching equipment, said impulse receiving means controlled directly by impulses received 15 over said line circuit if said line circuit is that of a station of said one class, and an intermediate impulse receiving means connected to the line circuit responsive to the extension thereof to said equipment if said line circuit is that of a station of said other class, said intermediate impulse receiving means effective to control said one impulse receiving means in accordance with the received impulses. 20
- 25 7. In an automatic switching control system, two classes of stations and line circuits therefor, impulse generating means of one kind at each station of one class for transmitting over its associated line circuit impulses of a certain character, impulse generating means of another kind at each station of the other class for transmitting over its associated line circuit impulses of a different character, switching equipment including a line impulse receiving relay, means for connecting the line circuit of a station of either class to said line relay, and means for energizing said line relay over said connected line circuit only when said connected line circuit is one which is associated with a station of said other class. 30
- 35 8. In an automatic switching control system, two classes of stations and line circuits therefor, impulse generating means of one kind at each station of one class for transmitting over its associated line circuit impulses of a certain character, impulse generating means of another kind at each station of the other class for transmitting over its associated line circuit impulses of a different character, switching equipment including a line impulse receiving relay and other impulse receiving means, means for connecting the line circuit of a station of either class to said line relay, means for energizing the line relay over the connected line circuit only when said connected line circuit is one which is associated with a station of said one class. 40
- 45 9. In a system such as that claimed in claim 7, other impulse receiving means, means effective to a predetermined length of time after the connection of a line circuit of a station of either class to said line relay to disconnect said line relay from said line circuit and to connect said other impulse receiving means to said line circuit, said last means rendered ineffective by the prior energization of said line relay over the connected line circuit only when said connected line circuit is one which is associated with a station of said other class. 50
- 55 10. In an automatic switching control system, 40

two classes of controlling stations and line circuits therefor, means at stations of one class for interrupting their line circuits to transmit impulses thereover, means at stations of the other class for transmitting impulses over their line circuits without interrupting said line circuits, switching equipment including a line impulse receiving relay and other impulse receiving means, means for associating the line circuit of a station of either class with said switching equipment, automatic discriminating means effective responsive to the association of the line circuit of either class with said switching equipment to determine if said line relay shall be connected to said line circuit, or, alternatively, if said other impulse receiving means shall be connected to said line circuit. 15

11. In an automatic switching control system, one class of line circuits effective to conduct direct current, another class of line circuits effective to conduct only current to which a condenser is transparent, discriminating means including a line relay, and means for causing a line circuit of either class to complete a series circuit including the winding of said relay and a source of direct current. 20

12. In an automatic switching control system, one class of line circuits effective to conduct direct current, another class of line circuits effective to conduct only current to which a condenser is transparent, discriminating means including a line relay, means for causing a line circuit of either class to complete a series circuit including the winding of said relay and a source of direct current, impulse receiving means, and means effective a predetermined interval of time after the connection of a line circuit of a station of either class to said line relay for disconnecting said line relay from said line circuit and connecting said impulse receiving means to said line circuit, said last means rendered ineffective by the prior energization of said line relay over the connected line circuit when the connected line circuit is one which conducts direct current. 30

13. In a telephone system, one class of subscribers' line circuits effective to conduct direct current, another class of subscribers' line circuits effective to conduct only current to which a condenser is transparent, automatic switches, means including one of said automatic switches for extending a connection to a subscriber's line circuit of either class, a relay for operating in correspondence with the switchhook of the subscriber's substation to which last said line circuit extends, intermediate controlling means, means effective under one condition for controlling said relay directly from said last line circuit, means effective under an alternative condition for placing said relay under control of said intermediate controlling means and for connecting said intermediate controlling means to said last line circuit. 40

14. In an automatic telephone system, subscribers' substations of one class having means for transmitting impulses of current to which a condenser is transparent over their line circuits, 45 subscribers' substations of another class having means for transmitting impulses of direct current over their line circuits, exchange equipment including a line impulse receiving relay and other impulse receiving means, automatic means responsive to the initiation of a call from a substation of either class for associating the line circuit of said substation with said exchange equipment, means responsive to the association of the line circuit of a substation of said one 50

- class with said exchange equipment for placing said line relay under the control of said other impulse receiving means and for placing said other impulse receiving means under control of said line circuit, means effective when the line circuit of substation of said other class is associated with said exchange equipment to cause said last line circuit to assume the direct control of said line relay. 5
10. 15. In a system such as claimed in claim 14, wherein said other impulse receiving means includes a pair of relays and means controlled conjointly thereby for connecting said pair of relays alternately to said line circuit. 10
15. 16. In a system for controlling automatic switches, a line circuit, means for transmitting over said line circuit impulses of current to which a condenser is transparent, impulse receiving means including two line relays and means for connecting said line relays alternately to said line circuit, said impulse receiving means effective to control the transmission of direct current impulses to said automatic switches. 20
20. 17. In a signalling system, a line, means for transmitting impulses thereover, a pair of impulse responding devices associated with the line and energized alternately thereover by successive ones in a train of impulses, an electrical circuit to be controlled, and means controlled conjointly by said devices for completing said circuit responsive to each energization of a particular one of said devices and for interrupting said circuit responsive to each energization of the other device. 30
25. 18. In a signalling system, a transformer, means for impressing voltage of a normal value upon the primary winding of said transformer, means for causing the normal value of the impressed voltage to be departed from for an interval of time, a pair of signal receiving devices, and a line circuit for said devices including a secondary winding of said transformer, the first of said devices responsive to current induced in the line circuit by the departure of said impressed voltage from said normal value, the second of said devices responsive to current induced in the line circuit by the reversion of said impressed voltage to said normal value at the end of said interval of time. 35
30. 19. In a signalling system, a circuit to be controlled, controlling means including, a transformer, means for impressing voltage of a normal value upon the primary winding of said transformer, means for causing the normal value of the impressed voltage to be departed from for an interval of time, a pair of signal receiving relays, and a line circuit for said relays including a secondary winding of said transformer, the first of said relays energized by current induced in the line circuit by the departure of said impressed voltage from said normal value to complete said first circuit, the second of said relays energized by current induced in the line circuit by the reversion of said impressed voltage to said normal value at the end of said interval of time to interrupt said first circuit. 40
35. 20. In a system for controlling automatic switches, a completed line circuit, means for transmitting impulses over said line circuit without interrupting the continuity thereof, impulse receiving means including two relays, means for connecting first said relay to said line circuit to operate responsive to an impulse transmitted over said line circuit, said first relay effective to prepare second said relay for operation, said second relay operated responsive to the succeeding impulse transmitted over said line circuit and effective to prepare said first relay for reoperation, said impulse receiving means effective to control the transmission of direct current operating impulses to said automatic switches. 45
40. 21. In a system for controlling automatic switches, a line circuit, another circuit inductively associated therewith, a source of current for said other circuit, means for interrupting said other circuit to effect the transmission of impulses over said line circuit, impulse receiving means including three relays, means for connecting first said relay to said line circuit to operate responsive to an impulse transmitted over said line circuit, said first relay effective to operate said second relay, said second relay effective upon operating to interrupt the operating circuit of said first relay and to prepare said third relay for operation, said third relay responsive to the succeeding impulse transmitted over said line circuit and effective to release said second relay, said second relay effective upon release to interrupt the operating circuit of said third relay and to prepare said first relay for reoperation, said impulse receiving means effective to control the transmission of direct current impulses to said automatic switches. 50
45. 22. In a system such as that claimed in claim 21 in which said first relay is also effective upon operating responsive to an impulse transmitted over said line circuit to establish a locking circuit to keep itself operated for the duration of the impulse, and said third relay is also effective upon operating responsive to an impulse transmitted over said line circuit to establish a locking circuit to keep itself operated for the duration of the impulse. 55
50. 23. In a system such as that claimed in claim 21, in which said first relay is also effective upon operating responsive to an impulse transmitted over said line circuit both to establish a locking circuit to keep itself operated for the duration of the impulse and to interrupt the operating circuit of said third relay, and said third relay is also effective upon operating responsive to an impulse transmitted over said line circuit both to establish a locking circuit to keep itself operated for the duration of the impulse and to interrupt the operating circuit of said first relay. 60
55. 24. In a system such as that claimed in claim 20, in which the length of time between the operation of the first said relay and the second said relay determines the length of the transmitted operating impulse, and the length of time between successive operations of either one of said relays determines the frequency of said transmitted operating impulse. 65
